UNITED STATES PATENT OFFICE.

CORNELIUS DWYER, OF AMSTERDAM, NEW YORK.

PLUMBER'S MELTING-POT.

SPECIFICATION forming part of Letters Patent No. 781,193, dated January 31, 1905.

Application filed March 14, 1904. Serial No. 198,058.

To all whom it may concern:

Be it known that I, CORNELIUS DWYER, a citizen of the United States, residing at Amsterdam, county of Montgomery, and State of New York, have invented certain new and useful Improvements in Plumbers' Melting-Pots, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a central vertical section of a plumber's solder-pot embodying this invention. Fig. 2 is a top plan view of the same with the handle partly broken away. Fig. 3 is a central vertical longitudinal section of a ladle embodying the invention.

The object of the invention is to avoid the confusion and loss due to the accidental or designed removal of pot-pieces of solder or lead from a plumber's pot or other vessel adapted to contain molten lead or solder.

Lead and solder for use in plumbing are ordinarily melted in an iron pot, from which such quantities of the molten metal are removed as are required at the time, the remainder being allowed to cool in the form of a pot-piece formed in the bottom of the vessel. Such pot-pieces are easily displaced or removed from the vessels heretofore employed for melting such metals, and the loss by theft and otherwise of such pot-pieces has been suffered without remedy by employing plumbers. Even without theft much loss is occasioned, due to the fact that it is almost impossible for persons of ordinary experience in the art to distinguish lead from solder when cold, and in case of doubt the pot-piece must be thrown into the scrap.

The present invention renders it impossible to remove from the containing vessel a pot-piece of any considerable size, so that not only is the theft of such pieces prevented, but by providing the containing vessels with distin-

guishing-marks to indicate the metal intended to be contained therein it is possible with ordinary care to prevent mistakes due to the mixture of such metals or to the substitution of one for the other.

In carrying out the invention the interior of the containing vessel is provided with undercut or overhanging portions, whereby the pot-piece is securely interlocked with the vessel-wall.

In Figs. 1 and 2 is shown an ordinary form of plumber's solder-pot 1, which in accordance with this invention has been provided with a groove 2, formed in its inner wall near the bottom of the pot, so as to produce undercut or overhanging portions of the wall adapted to interlock with a pot-piece, formed by the hardening of molten metal permitted to remain in the vessel until cooled below fusing temperature. Any desired number of such grooves may be employed, and they may be extended wholly or only partly around the interior of the pot. A row of short grooves 3 is shown just above the continuous groove 2 in Figs. 1 and 2. In Fig. 1 the handle 4 of the pot is shown provided with the distinguishing-marks "S O L D E R," to indicate the contents of the pot.

As a means to prevent the loss or improper mixture of very small pot-pieces, too small to be held by the undercut portions of the pot-wall, the bottom of the pot may be formed with either raised or sunken characters, adapted to form upon the bottom of the pot-piece, however small, reversely-molded characters indicating the nature of the metal for which the vessel is intended. Thus the pot shown in Figs. 1 and 2 being formed with the inverted characters "S O L D E R" sunken in its bottom will form said characters in proper position upon the bottom of the pot-piece to indicate that said pot-piece is solder, so that if the pot-piece should become separated from the pot it could not be mistaken for metal different from that indicated by said characters. The molded characters thus formed upon the pot-piece by interlocking with the corresponding depressed portions of the pot-bottom serve also to prevent a rotative movement of the pot-piece, which if permitted

might make it possible to remove from the pot the pot-piece if it were so small that comparatively little of its periphery extended beneath the overhanging portions of the pot-wall.

5 In Fig. 3 is shown a ladle 5, having inwardly-projecting lugs 6, which form overhanging or undercut portions, whereby the pot-piece will be retained in substantially the same manner as by the construction shown in 10 the other figures and above described.

What I claim as new, and desire to secure by Letters Patent, is—

15 1. A vessel for containing molten metal having interior undercut portions adapted to interlock with a pot-piece formed by the hardening of the contained metal.

2. A vessel for containing molten metal having near its bottom interior undercut portions adapted to interlock with a pot-piece formed by the hardening of the contained metal, and having in its bottom characters formed by irregularities in its bottom surface adapted to form upon the bottom of a pot-piece molded characters whereby rotation of the pot-piece is prevented. 20 25

In testimony whereof I have hereunto set my hand this 1st day of March, 1904.

CORNELIUS DWYER.
